KITCHEN CABINET

Raymond Loewy, New York, N.Y.
(% C.E.I., 39 Avenue d'Iena, Paris 16e, France)

Filed May 15, 1970, Ser. No. 23,005

Term of patent 14 years

Int. Cl. D6—04

U.S. Cl. D33—19

FIG1

FIG2

FIG. 1 is a front perspective view of a kitchen cabinet showing my new design; and

FIG. 2 is a rear perspective view thereof.

The slats seen on the front panels in FIG. 1 extend across the top of the cabinet.

I claim:

The ornamental design for a kitchen cabinet, as shown and described.
